UNITED STATES PATENT OFFICE.

CHARLES T. BONNABEAU, OF NEW YORK, N. Y.

BAR-SOAP HOLDER.

1,198,184.

Specification of Letters Patent. Patented Sept. 12, 1916.

Application filed November 16, 1915. Serial No. 61,769.

To all whom it may concern:

Be it known that I, CHARLES T. BONNABEAU, a citizen of the United States, and resident of the city of New York, borough 5 of Brooklyn, in the county of Kings and State of New York, have invented a new and Improved Bar-Soap Holder, of which the following is a full, clear, and exact description.

10 This invention relates to soap holders, and has particular reference to such holders as are adapted to economize in the use of soap and to enhance the cleanliness of the devices with respect to similar devices com- 15 monly in use.

Among the objects of the invention, therefore, is to provide a soap dish or holder adapted for attachment to the back of a washstand or the like, said holder comprising 20 two separable parts, one above the other, the lower part being arranged to receive the drip from the wet bar of soap and from which the drip water may readily be wiped or sponged.

25 With the foregoing and other objects in view, the invention consists in the arrangement and combination of parts hereinafter described and claimed, and while the invention is not restricted to the exact details of 30 construction disclosed herein, still for the purpose of illustrating a practical embodiment thereof reference is had to the accompanying drawings, in which like reference characters designate corresponding parts in 35 all the views, and in which—

Figure 1 is a perspective view showing a preferred embodiment of the invention; Fig. 2 is a plan view of the same; and Fig. 3 is a vertical sectional view on the line 40 3—3 of Fig. 2.

Referring more particularly to the drawings I show a main part 10 comprising a vertical back 11 and a forwardly projecting horizontal cup-like part 12. The back is 45 provided with a plurality of slots 13 through which T-head screws or bolts 14 are adapted to pass. The screws are adapted to be turned into the wall or other support, and with their heads extending trans- 50 versely of the slots they will serve to lock

the main part firmly but removably to said support. This main part is preferably made from sheet metal stamped and bent into form, the side portions 12' being soldered or otherwise secured, making a watertight cup. 55 The back 11 is struck forwardly forming a pair of open-topped sockets 15 arranged preferably on the same horizontal line and at any desired distance below the top edge of the back.

60 The other main part of the holder consists of a rack 16, the main portion of which, like the other main part, above described, is made of sheet metal stamped and bent into form approximately saucer-shape and 65 adapted to be supported in a horizontal plane above the cup 12. The bottom of the rack is provided with a plurality of perforations or slots 17 arranged between parallel upwardly formed ribs 18. The 70 front and side edges of the rack are rolled or turned over a metal rib 19, the free ends of which are turned upwardly at the rear edge of the rack forming a pair of spaced hooks 20 adapted to be inserted into the 75 open-topped sockets 15, providing therefore a simple, cheap, and yet neat and reliable detachable connection between the rack and the main holder part. A wet bar of soap placed upon the rack is received and sup- 80 ported upon the ribs 18, the drip from the soap passing freely through the holes 17 into the cup 12, where it will be collected and thus prevented from splashing upon and soiling the top of the washstand or the 85 like. This manner of supporting the soap bars insures a free drying thereof without waste, the waste ordinarily being incident to the lying of a bar of soap in a pool of water. Either part of the holder may 90 readily be cleansed while supported in position, or for any other purpose the same may be removed if desired. The soiled water dripping into the cup 12 may be easily sponged therefrom if it is not desired to re- 95 move the holder from the wall.

I claim:

The herein described holder for bar soap comprising a main part including a vertical back and a horizontally projecting imper- 100

forate cup, said back being provided with a pair of open-topped sockets, and a rack including a perforated body and a rib binding the front and side edges of the body, 5 said rib having free ends bent upwardly and thence downwardly forming hooks to be removably secured in said open-topped

sockets, said rack also having a plurality of upwardly projecting ribs between the perforations thereof.

CHARLES T. BONNABEAU.
